ELECTRON DISCHARGE DEVICE

Harry R. Seelen, South Orange, and Kenneth M. McLaughlin, Arlington, N. J., assignors, by
meane assignments, to Radio Corporation of
America, New York, N. Y., a corporation of
Delaware

Application May 28, 1938, Serial No. 210,648

4 Claims. (Cl. 250—27.5)

Our invention relates to electron discharge devices, particularly to electrode assemblies for such devices.

The electrodes of an electron discharge device are usually concentric cylinders with side rods or ears extending beyond the ends of the cylinders to engage holes in insulating spacers at the ends of the assembly. It is difficult to telescope small electrodes and thread their extensions in the holes without damage to the parts, especially when the inter-electrode spacing and the holes are small. Further, the electrical characteristics of the conventional tube cannot be changed in manufacture without changing the size and shape of many of the parts in the electrode assembly.

An object of our invention is an electron discharge device with electrodes which are easy to assemble, rugged in construction, and inexpensive to manufacture.

Another object of our invention is an electrode assembly which may be easily made with parts that are interchangeable in a number of tubes of different electrical characteristics.

An electrode assembly constructed according to our invention comprises a plurality of planar type electrodes held in parallel spaced relation with vertical sheet-like insulating spacers adjacent the side edges and normal to the plane of the electrodes. Extensions such as ears or lugs on the side edges of the electrodes rest against steps or notches in the edges of the spacers in such a way that the length of the risers between the treads of the steps, on which the extensions bear, fixes the distances between the electrodes. Changes in electrode spacing may be made in manufacture, with corresponding changes in electrical characteristics, by merely changing the configuration of the stepped edges of the spacers.

The characteristic features of our invention are defined with particularity in the appended claims and preferred embodiments are described in the following specification and shown in the accompanying drawing in which Figure 1 is a perspective view of an electrode assembly of our invention, Figure 2 is a detailed expanded view of electrodes constructed according to our invention; Figure 3 is an elevation of a shielded mount of our invention, Figure 4 is a detailed view of a shield which may be used in our improved tube, and Figure 5 is a detailed view of one cathode which may be used in our improved mount.

An electron discharge device with an electrode assembly constructed according to our invention comprises an envelope 1 closed at its lower end

with a stem or header 2 in which is sealed a plurality of lead-in conductors 3 joined at their upper ends to the electrodes of our novel electrode assembly. The electrode assembly chosen for illustrating our invention comprises a cathode 4, control grid 5, screen grid 6, suppressor grid 7, and anode 8. The cathode, Figure 2, may conveniently comprise two grooved strips of refractory metal jointed along their edges to form a hollow sleeve in which an insulated heating element may be inserted. The strips of metal are blanked out with two pairs of parallel ears or lugs 9 which engage at their ends holes in the central portion of the two insulated spacers 10.

Each of the grid electrodes 5, 6 and 7 is a rectangular frame with parallel grid wires welded at their ends to the side members of the frame, which like the cathode are provided with two pairs of outwardly extending ears or lugs 11 on the side edges of the frame. The anode is a rectangular flat sheet of metal with the same outside dimensions as the frames of the grids and is provided with two pairs of outwardly extending ears or lugs 12.

The insulating spacers 10 of our improved mount are flat sheets of insulating material such as mica and as shown in Figure 1 are provided with a plurality of steps 13, the steps extending diagonally across the corners of the spacer. When assembled the ear or lug extensions of the electrodes bear against the tread 14 of the steps and the spacing between the electrodes is determined by the length of the risers 15, Figure 5, between the tread. The ears on each electrode may conveniently be elongated and registering ears joined as by spot welding at 16 at their ends along the vertical center line of the spacer.

Our improved electrodes are particularly easy to assemble. As distinguished from the conventional mount where electrodes are telescoped together and side rods are threaded through small openings, the planar type electrodes of our assembly are simply laid in proper order between the spacers with the ear extensions lying upon the steps of the spacer. The ears are flattened against the spacers and their registering ends joined together. The ends of upstanding lead-in wires 3 are then joined to the ends of the electrode ears, preferably at 16, to mechanically support the electrode assembly and to electrically connect each electrode with its lead-in conductor. Should additional strength be desired in supporting the assembly upon the stem, a U-shaped bracket 17 may conveniently be welded to the

header with its upper ends joined to the strap 18 encircling the mount. The shell is then joined to the stem, and the envelope exhausted and based in the usual manner.

- 5 The anode of our improved electrode mount is easily shielded from the other electrodes in the tube. The electrostatic shielding of the screen grid may be extended to the walls of the envelope with thin metal plates 19, Figure 4, 10 joined to or formed integrally with the ends of the screen grid frames, as shown in Figure 3. The shields are semi-circular and are bent normal to the plane of the screen grid to bring the curved edges of the shields close to or into contact with the inner surface of the envelope. The 15 shields may serve to center the electrode assembly within the envelope, and the depending ears 20 on the shields joined at their ends to the ends 16 of the screen grid ears, completely isolate the anode from the other electrodes.

In Figure 5 an alternative means for supporting the cathode in the mount is shown. The sleeve of the cathode 4, which may be exteriorly coated with electrode emissive oxides and which 25 carries internally an insulated heating element, is joined at its ends to wire-like spring fingers 21 curved outwardly and hooked into holes in the spacers. It will be obvious to those skilled in the art that many forms of cathodes and means of 30 mounting the cathodes may be employed in the manufacture of our improved electrode assembly without departing from the scope of our invention.

Electrodes assembled according to our invention 35 may be stacked between the spacers by automatic machinery and thus obviate the tedious and costly hand work necessary in threading the usual side rods through small spacer holes. Our improved electrode assembly is adapted to 40 economical manufacturing technic where many tubes, although similar in construction must have different electrical characteristics. Some tubes, for example, differ only in the spacing between electrodes. When constructed according to our 45 invention these different types of tubes may be made merely by selecting insulating spacers with the proper step configuration.

Our improved electrode assembly is particularly adapted for beam forming. The parallel 50 level wires of adjacent grids may be easily aligned and held in place by the contact between the edges of ears 11 and the risers 15 of the steps. The opening in the grid frames may, if desired, be successively large progressing from the 55 cathode to the anode, to afford good beam forming characteristics.

An electron discharge device constructed ac-

cording to our invention is easy to assemble, is rugged in construction and inexpensive to manufacture.

We claim:

1. An electron discharge device comprising a 5 plurality of parallel planar type electrodes, each electrode being rectangular and having two ears extending from each of the side edges of the electrode, two flat spacers of insulating material normal to the plane and adjacent the side edges 10 of the electrodes, steps along the edges of the spacers with the ears of the electrodes bearing against said steps for holding the electrodes in insulated spaced relation.

2. An electrode assembly comprising a plurality 15 of parallel planar electrodes, each electrode being rectangular and having ear extensions on each of its side edges, two elongated flat insulating spacers against said side edges and normal to the plane of the electrodes, the width of each 20 elongated spacer being different at its center from its ends, the edges of the spacers being stepped, means for holding the said extensions against said steps, the length of the risers between the treads of said steps being substantially 25 equal to the spacing between adjacent electrodes.

3. An electrode assembly comprising a plurality of planar electrodes held in parallel spaced relation, two vertical sheet-like insulating spacers adjacent the side edges of said electrodes and 30 normal to the plane of the electrodes, ear extensions on the side edges of the electrodes resting against edges of the spacers, the point of contact between said edges and extensions of the different electrodes being successively stepped 35 inwardly toward the center line of the spacers, the length of the risers between the treads of the steps being substantially equal to the distances between the electrodes.

4. An electrode assembly comprising a grid 40 with a rectangular metal frame having end and side members, parallel wires joined at their ends to said side members, a rectangular metal plate of substantially the same dimensions as said grid, ears on the side edges of said plate and on said side members, the ears on the plate and on the grid being spaced different distances from the ends of the electrodes, two spaced parallel insulating spacers normal to the plane of said electrodes, the edges of said spacers being stepped, means for holding the plate ears and the grid ears against adjacent steps, and a cathode supported on said spacers in cooperative relation with the grid and plate.
